Primary Examiner — Rhea Shields(74) *Attorney, Agent, or Firm* — Ostrolenk Faber LLP(57) **CLAIM**

The ornamental design for an apparatus for acupressure, as shown and described.

DESCRIPTION

1. Apparatus for acupressure

1.1 is a front view;

1.2 is a rear view;

1.3 is a top, rear and left side perspective view;

1.4 is a right side view;

1.5 is a bottom view;

1.6 is a top, right side perspective view;

1.7 is a front, top right side perspective view; and

1.8 is a top view thereof.

In the reproductions, the broken lines are for the purpose of illustrating environment only and form no part of the claimed design.
